UNITED STATES PATENT OFFICE.

SAMUEL CABOT, OF BOSTON, MASSACHUSETTS.

PROCESS OF MAKING CARBON DIOXIDE.

SPECIFICATION forming part of Letters Patent No. 415,090, dated November 12, 1889.

Application filed June 7, 1889. Serial No. 313,495. (No specimens.)

To all whom it may concern:

Be it known that I, SAMUEL CABOT, a citizen of the United States, residing at Boston, in the county of Suffolk and State of Massachusetts, have invented certain new and useful Improvements in the Manufacture of Carbonic-Acid Gas, of which the following is a specification.

The object of my invention is the production of pure carbonic-acid gas in large quantities and at moderate cost.

In a United States patent granted to me on the 29th day of March, 1887, and numbered 359,996, a method is described of treating broken limestone alternately with direct heat and with steam, and collecting or using the carbon dioxide which is disengaged, while the steam is passing over the hot carbonate before or after the condensation of the watery vapor. In said patent the necessity was stated of alternating continuously the two acts of the process cited, so as perpetually to restore the heat which the carbonate lost during the passage of the steam by the direct action of fire thereon, and then, by means of fresh steam following each heating, to effect the decomposition of additional quantities of limestone. I have discovered, and experience has proved the practicable nature of the discovery, that the alternation described is not a necessary condition of success, that it is not even necessary (though sometimes desirable) to subject the broken limestone to a preliminary heating by direct fire.

My present invention, in its simplest form, consists, essentially, in treating broken limestone with strongly superheated steam only. I have found that steam raised to a temperature somewhat below that of melting copper—say about 2,000° Fahrenheit—is capable of expelling the carbon dioxide from limestone when the latter is enveloped in a continuously-changing atmosphere of such steam.

In the drawing which forms a part of this specification, the figure represents the apparatus which may be employed to carry out my process.

The shaft 10 of the kiln is shown in vertical section. Into this the broken limestone is charged, the flat cover 12 being removed for that purpose. When this cover is restored to its place and cemented round about

its edges with fire-clay, and the iron door 14 below has also been properly screwed up against suitable packing, the superheated steam is admitted through the channel 16 from the superheater 18 to the lower part of the kiln.

The best form of superheater need not be here discussed, as the subject is well understood, and any efficient construction may be employed. I show this necessary part of my apparatus therefore only in elevation, and indicate with dotted lines the iron and fire-clay tubes which may be employed, as also the position of the boiler in which the requisite steam is generated, the waste heat from the furnace below being used for that purpose.

When the steam from the superheater 18 enters the closed kiln through the channel 16, its heat will first be expended solely in raising the temperature of the mass of cold limestone in the shaft 10. Pending this heating the valve at 22 is open, so that the cooled steam in the kiln is permitted to discharge and to give place for a continuous stream of exceedingly hot steam through the channel 16. I have found that under these circumstances the temperature at which decomposition of the calcium carbonate begins is remarkably low; but that as the temperature of the stone is raised above that the rapidity with which carbon dioxide is evolved is greatly increased, so that it may be said generally that the more efficient the superheater the better and more economical will be the result. When once the decomposition has been started in a kiln of this sort, it can be maintained indefinitely. This is done by feeding at intervals small quantities of broken limestone above and raking away equivalent quantities of burnt lime from the discharge-opening below, which is then to be quickly and tightly closed by the door 14, the interruption to the continuous evolution of gas being made as short as possible. The quantity of quicklime produced during each interval will extend a short way up the shaft of the kiln close above the channel 16. The gas and steam as they escape through the valve 22 may be cooled by suitable methods,

so as to precipitate the latter as water, in which case a very pure carbonic acid will be

obtained; or they may be passed or forced at once into receptacles containing chemical substances the union of which with carbonic acid is desired.

5 When the whole charge of broken limestone in the shaft 10 is cold, and when the kiln itself is cold throughout, as it must be at the beginning of an operation such as that I have described, it is quite feasible to heat up to 10 the gas-evolving point by the aid of superheated steam alone; but I prefer to do this by direct heat, not only because the way hereinbefore set forth is slow and costly, but also for the more vital reason that the large condensation of water which takes place upon the cold stone and fire-brick is liable to injure the kiln very seriously. I therefore prefer to avail myself of direct heat for this first heating, and I accomplish the same by forcing in under suitable pressure an inflammable gas, which may be supplied by the tubes 15 and 26, and atmospheric air to support combustion through independent tubes or through in-draft-openings, as indicated by the arrows at 28, all leading to the combustion-chamber 30, located near the lower part of the shaft. While the flame so distributed and controlled as to quantity and quality by the valve 36 and the annular opening at 28 is 20 raising the temperature of the kiln and its contents, the cover 12 is off the top, so that the products of the combustion may escape, especially the large volume of nitrogen, which dilutes whatever carbonic acid may be formed 25 under such circumstances; but as soon as ever the necessary heat has been reached both the inflammable gas or vapor and the air which enabled it to burn are cut off, the cover 12 closed, and the subsequent running 30 of the kiln carried on with superheated steam alone.

In the figure the design of the kiln therein shown in section is well adapted for the ends in view; but it is obvious that it might be varied 45 infinitely in form and plan and still be as suitable for the consummation of the process I have invented. Such modifications in construction will be desirable, for instance, when the complete decomposition of one large 50 charge of calcium carbonate is accomplished and all the caustic lime removed before the next lot is introduced. Such a procedure is often very convenient, especially when suit-

able fuel is to be had to heat without difficulty the large mass in the first instance. My process will then be found especially favorable, as there is little or no danger of over-heating the burnt lime, the value of which by-product is considerable.

In this specification the special devices by 60 means of which my process is worked are not claimed, as it is intended that they should form the subject-matter of a future application for patent.

What I claim is—

1. The improvement in the manufacture of carbon dioxide, which consists in first raising the temperature of calcium carbonate to the degree requisite for its decomposition in an atmosphere of water-vapor by the action of 70 superheated steam thereon, and then maintaining such temperature and decomposition by continuing the flow of superheated steam over said carbonate until the disengagement of its carbon dioxide is accomplished, substantially as described.

2. The improvement in the manufacture of carbon dioxide, which consists in first raising the temperature of calcium carbonate to the degree requisite for its decomposition in an atmosphere of water-vapor by direct heat from any suitable source, then cutting off and removing the same, and then maintaining such temperature by a continued flow of superheated steam over said carbonate until the 85 disengagement of its carbon dioxide is accomplished, substantially as described.

3. In the manipulation of calcium carbonate for the production of carbon dioxide and quicklime, the preliminary heating of said carbonate by the direct application of burning gases, then cutting off the gaseous fuel and admitting a current of superheated steam, whereby the necessary temperature is maintained and the desired decomposition effected, 95 substantially as described.

4. In the decomposition of calcium carbonate for the production of a mixture of pure carbon dioxide and water-vapor, the treating of said carbonate with a current of superheated steam at or near the temperature of melting copper, substantially as described.

SAM. CABOT.
